UNITED STATES PATENT OFFICE

91,717

DESIGN FOR A MERCHANTISE DISPLAY FIXTURE

Walter W. Maguire, Watertown, Mass.

Application August 29, 1933, Serial No. 49,164

Term of patent 14 years

To all whom it may concern:

Be it known that I, WALTER W. MAGUIRE, a citizen of the United States, residing at 112 Charles River Road, Watertown, in the county of Middlesex and State of Massachusetts, have invented a new, original, and ornamental Design for a Merchandise Display Fixture, of which the following is a specification, reference being had to the accompanying drawing, forming part thereof,

In the drawing, Fig. 1 is a vertical perspective view of the fixture, showing my new design.

Fig. 2 is a top perspective view of the fixture shown in Fig. 1, and

Fig. 3 is a horizontal perspective view of the same fixture.

I claim:

The ornamental design for a mechandise display fixture, as shown.

WALTER W. MAGUIRE.
